UNITED STATES PATENT OFFICE.

ROBERT G. HANFORD, JR., OF NEWARK, NEW JERSEY, ASSIGNOR TO THE HANFORD, PECKHAM & McCANCE COMPANY, OF SAME PLACE.

BRIDLE-BIT.

SPECIFICATION forming part of Letters Patent No. 337,578, dated March 9, 1886.

Application filed June 11, 1885. Serial No. 168,353. (No model.)

To all whom it may concern:

Be it known that I, ROBERT G. HANFORD, Jr., of Newark, in the county of Essex and State of New Jersey, have invented a certain 5 new and useful Improvement in Bits, of which the following is a specification.

My improvement relates to bits such as are used for horses and other animals.

I will describe in detail a bit embodying 10 my improvement, and then point out the novel features in claims.

The accompanying drawing is a longitudinal section of a bit embodying my improvement.

15 A designates the cheeks or rings of the bit. They may be of any desired shape. As here shown, they consist of ring-like portions *a*, having portions *b* extending crosswise thereof at about the diameter of the rings. The portions 20 provided with loops, to which cheek-straps may be secured, extend upwardly from the rings *A*, and bar-like portions provided with apertures, to which the reins may be secured, extend downwardly from said rings.

25 The portions *b* have, as here shown, cylindrical portions *c*, extending loosely through apertures in heads *d* *d'* of the bar or mouth-piece *B* of the bit. The heads *d* *d'* of the bit are connected together by a cross-bar, *e*, of 30 less diameter than said heads. The heads *d* may be cast with the cross-bar, if desirable, while the other, *d'*, is free to be secured to and removed from the cross-bar, preferably by means of screw-threads. About the cross-

35 bar *e* of the bit I secure paper, *C*. The paper may be secured about said cross-bar by compression, if desirable; but I prefer to cut rings or washers *f*, of paper, of suitable thickness and diameter, and place them, one after the 40 other, upon the cross-bar until the latter is

full. They are then tightly pressed together upon the cross-bar, after which the head *d'* may be screwed or otherwise secured upon the free end of the cross-bar.

The paper from which the washers *f* are 45 composed is treated with chloride of zinc. This may be incorporated with the paper, either during the process of manufacture of the latter and before it is made into washers, or the washers, after being made, may be treated with 50 the chloride of zinc, preferably in the form of a solution, which will be absorbed by the paper.

A bit having a mouth-piece covered with paper which has been treated with chloride of 55 zinc is advantageous, because the paper presents a smooth pleasant surface, which will not pinch or skin a horse's mouth in cold weather, while the chloride of zinc acts medicinally upon sore and tender mouths, healing and strengthening them. Paper washers are also very durable and cheap.

Bits embodying my improvement may be made of two sections having a hinge-like connection at the middle of the length of the 65 bit. The sections will have at the meeting ends shoulders against which the paper will be pressed.

What I claim as my invention, and desire to 70 secure by Letters Patent, is—

1. A bit provided with a mouth-piece covered with paper treated with chloride of zinc, substantially as specified.

2. A bit provided with a mouth-piece covered with paper rings or washers treated with 75 chloride of zinc, substantially as specified.

R. G. HANFORD, JR.
